UNITED STATES PATENT OFFICE.

WALTER DENNISON CASE, OF GRANBY, CONNECTICUT.

CATTLE-STANCHION.

SPECIFICATION forming part of Letters Patent No. 633,799, dated September 26, 1899.

Application filed January 11, 1899. Serial No. 701,821. (No model.)

To all whom it may concern:

Be it known that I, WALTER DENNISON CASE, of Granby, in the county of Hartford and State of Connecticut, have invented a new and Improved Cattle-Stanchion, of which the following is a full, clear, and exact description.

This invention relates to a cattle-stanchion designed for stables, ships, and other places where cattle are to be kept, and comprises an oblong frame inclosing the neck of an animal and having one side removable and provided with a latch by which to hold it, so that when desired the stanchion may be opened to receive or release the animal.

This specification is the disclosure of one form of the invention, while the claim defines the actual scope thereof.

Reference is to be had to the accompanying drawings, forming a part of this specification, in which similar characters of reference indicate corresponding parts in all the views.

Figure 1 is a front elevation of the invention with parts in section. Fig. 2 is an end elevation of the invention with parts in section. Fig. 3 is an enlarged front view of the upper part of the stanchion with parts broken away and other parts in section. Fig. 4 is a fragmentary edge elevation illustrating the latch. Fig. 5 is an elevational view of the lower part of the stanchion with parts broken away and other parts in section, and Fig. 6 is a detail section on the line 6 6 of Fig. 3.

The invention embodies an integral rigid side section or bar 10, the ends of which are curved inward and fitted between the cheek-plates 11 and 12, respectively, of the arc-shaped upper end section 14 and the arc-shaped lower end section 15. The bar 10 is held rigidly between the cheek-plates 11 and 12 by means of bolts 16. The other side of the stanchion has a removable bar or section 17, the lower end of which is rounded to fit into a socket 18, formed at the end of the section 15 opposite the cheek-plates 12. The upper end of the bar 17 has a cavity 18^a therein, overhanging which is a plate 19. The upper end of the bar 17 is adapted to fit between two flaring cheek-plates 20, formed on the upper section 14 opposite the cheek-plates 11, the inward movement of the bar 17 being limited by a short shoulder 21, formed between the cheek-plates 20.

Adjacent to the cheek-plates 20 a swinging latch is pivoted on a pin 22, held rigidly in the section 14. This latch comprises a hook 23, engaging the plate 19 and extending into the cavity 18^a. The latch also comprises a thumb-piece 24, to permit the manipulation of the latch, and a heel 25, to which is connected a retractile spring 26, attached also to the section 14 and serving to throw the hook 23 against the plate 19, as shown in Fig. 3.

The sections 14 and 15 have sockets 26^a and 27 formed therein, such sockets respectively receiving the balls 28 of the rods 29, which extend upwardly and downwardly from the stanchion and are connected by suitable swivels 30 with supports 31, forming parts of the cattle-stalls. By means of the balls 28 and sockets 26^a and 27 the rods 29 are connected with the stanchion, so that the stanchion may be moved about to accommodate itself to the movements of the animal, and owing to the swivels by which the rods 29 are mounted on the parts 31 the rods are permitted to have free movement.

The arc-shaped upper and lower sections 14 and 15, with the rigid side bar 10, form a durable structure, which insures the proper rigidity of the stanchion and prevents the sagging of the parts, which defect generally exists in the usual rectangular stanchions.

Having thus described my invention, I claim as new and desire to secure by Letters Patent—

A cattle-stanchion, having a rigid side section, arc-shaped end sections, one end of each of which is rigidly fastened to the adjacent end of the rigid side section, whereby to form an oblong space to receive the neck of the stock, a removable bar forming a second side section, the ends of the bar being adapted to fit loosely in the respective adjacent ends of the end sections, a plate secured to one end of the bar, and a latch pivoted on the upper end section and having a hook adapted to engage under the plate to removably hold the bar in place.

WALTER DENNISON CASE.
